UNITED STATES PATENT OFFICE.

SUSAN M. PERKINS, OF LANSING, KANSAS.

BOOK OR MUSIC HOLDER.

SPECIFICATION forming part of Letters Patent No. 408,428, dated August 6, 1889.

Application filed September 15, 1888. Serial No. 285,548. (No model.)

To all whom it may concern:

Be it known that I, SUSAN M. PERKINS, of Lansing, in the county of Leavenworth and State of Kansas, have invented a new and useful Improvement in Book or Music Holders, of which the following is a specification.

My invention is an improvement in the class of book or music holders which consist of spring-clamps secured and adapted to slide toward or from each other upon a flanged or slotted bar. I employ a stretched wire support for the clamps in place of such flanged or slotted bar, and thereby attain several important advantages.

15 In the accompanying drawings, Figure 1 is a plan view of my improved book, music, or other holder, and Fig. 2 is an enlarged detailed perspective view of one of the clamps, the principal parts thereof being shown separated.

In the embodiment of my invention I employ two clamps A A, which consist each of a base-plate *a* and an upper plate *a'*, having, preferably, the form of an index or hand 25 formed with pendent apertured lugs or ears *a²* *a²*, fitting down alongside of additional apertured lugs or ears *a³* *a³*, supplied to the base-plate *a*. The apertured lugs or ears *a²* *a³* of the plates *a* *a'* receive and are connected together by means of a pivot-bolt *b*, the ends of which are treated similarly to the process of riveting, preventing its displacement. The upper or index plates *a* are thus pivoted or 30 articulated upon the base-plates *a*, thereby forming levers, the longer arms of which do the holding. Interposed between each base-plate *a* and upper or index plate *a'* is a spring *c*, preferably formed of spring metal or wire, which is wound or coiled about at its middle 35 upon the pivot-bolt *b*, one portion resting upon the base-plate and its other portion bearing against the shorter arm of the upper plate or lever. The springs effect the holding of the longer arms of the levers or upper 40 index-plates down in forcible contact with the article held thereby, as presently more fully disclosed.

The clamps A A are applied to and adjustable upon a stretched wire support B. As 45 shown, the latter consists of two strands of a

single wire whose looped ends are secured to a rack by means of screws or pegs *d*. It is obvious, however, that two separate wires might be employed and each provided with loops or eyes at its ends to receive the aforesaid screws or pegs.

55 The wire support B does not require to be specially constructed or manufactured for the purpose, and is as little obtrusive as possible when applied to any music-rack, which is effected by merely inserting the screws or pegs *d*, so as to stretch the wire taut, as shown.

The wires or wire strands B B pass through eyes *e*, formed integrally with the base-plate *a* of the clamps A.

65 The eyes or loops *e* are made in the base-plates by slitting the same transversely, and in parallel planes at suitable intervals apart, and then sinking or indenting the surface of the plates intermediately of the slits, bowing 70 the metal downward below the lower surface of the plates and leaving end apertures for the passage therethrough of the lengths of wire, the latter thus being held between the downwardly-bowed portions of the loops or 75 eyes and the bottom of the base-plates. From this it will be seen that the clamps are capable of a sliding movement or adjustment upon the wire or supporting media to adapt them to hold books, sheet-music, or similar matter, 80 of whatever width or size, and to hold the same effectively. This invention is also simple, cheap, and readily operated.

Having thus fully described my invention, what I claim, and desire to secure by Letters 85 Patent, is—

In a book or music holder, the combination, with the stretched two-strand wire support B, having looped ends, of the clamps, each 90 consisting of the spring-actuated lever *a'* and the base-plate *a*, pivoted to said lever and provided with loops *e*, which are formed of inwardly-bent portions of said plate and embrace the wire strands, thus attaching the 95 clamps adjustably to the latter, as shown and described.

SUSAN M. PERKINS.
